WITNESS

Patented Feb. 24, 1925.

UNITED STATES PATENT OFFICE.

JAMES W. FALK, OF LITTLE FALLS, MINNESOTA.

REINFORCED-CONCRETE RAILWAY TIE.

Application filed March 21, 1924. Serial No. 700,874.

To all whom it may concern:

Be it known that I, JAMES W. FALK, a citizen of the United States, residing at Little Falls, in the county of Morrison and State of Minnesota, have invented new and useful Improvements in Reinforced-Concrete Railway Ties, of which the following is a specification.

The object of my said invention is the provision of a railway tie of reenforced concrete constructed in such manner that the proportion of metal to each concrete body is small in weight, and also constructed in such manner that a rail may be expediently and strongly secured on the tie.

To the attainment of the foregoing, the invention consists in the improvement as hereinafter described and definitely claimed.

In the accompanying drawings, forming part of this specification:—

Figure 1 is a complete plan view of a tie constructed in accordance with my invention.

Figure 2 is an enlarged detail view showing a portion of one tie body or section partly broken away to illustrate the arrangement in the concrete of one metallic rail support and its appurtenances.

Figure 3 is a view of a portion of the tie at right angles to Figure 1.

Figure 4 is an enlarged detail vertical section illustrating the portion shown in Figure 3.

Figure 5 is a detail horizontal section taken in the plane indicated by the line 5—5 of Figure 4.

Figures 6 and 7 are perspectives of parts hereinafter explicitly referred to.

Figure 8 is a perspective of the block comprised in my improvement.

Figure 9 is a fragmentary side elevation showing the connection of the two sections of the tie.

Similar numerals of reference designate corresponding parts in all of the views of the drawings.

In the preferred embodiment of my invention my novel tie comprises two bodies or sections 1 of appropriate concrete arranged end to end in slightly spaced relation and each adapted to support one rail 2.

The said bodies or sections 1 are preferably shaped as illustrated, and they are connected together through the medium of links 3 having eyes 4 and threaded ends 5, the eyes 4 being designed to receive trans-

verse bolts 6 secured in the bodies or sections 1 adjacent to the ends thereof and the threaded end portions of the bolts being designed to extend through eyes on the transverse bolts, and the links and bolts being adapted to be secured in working relation as illustrated through the medium of nuts 7.

In each concrete body or section 1 are longitudinal dished metallic reenforcing rods 8 with hooked ends 9* to engage the before mentioned transverse bolts 6. Also

in each concrete body or section 1 and preferably in the center thereof is a metallic rail support 9. The said rail support 9 is

provided with lateral base extensions 10 to anchor it in the concrete and is also provided with an upstanding web 11 disposed lengthwise of the tie body. It will also be

noted by reference to Figure 4 that the metallic support 9 is provided in its web 11 with transverse apertures 12 designed to receive concrete as designated by 13 with a view to enabling the concrete occupying the apertures 12 to assist in holding the support

9 in the body 1. In its upper edge the support 9 is recessed at 14 to receive a block 15 of wood or other appropriate resilient material on which the rail 2 is directly superimposed, this in order that the rail may

be supported in a cushioned manner. It will also be noticed that the web 11 of the support 9 is increased in thickness at 15*,

Figure 5, the thickened portion 15* being

chambered as designated by 16. At 17 and 18 the support 9 and the block 15 are provided with coincident recesses for the reception of a reversible loose key 19 which is

adapted to rest against one edge of the base of the rail 2 to hold the latter against lateral deflection or movement in one direction. It will also be noticed that the key 19 is calculated to prevent movement

of the block 15 relative to the tie body 1 in the direction of the length of the rail

2. At the opposite side of the rail seat, with reference to the key 19, the support 9 is shaped to seat a rail clamping member

20, the said member 20 being provided with an aperture 21 and a shoulder 22 to abut

against the support 9 and being also provided with a bifurcation 23 to receive an

upstanding portion on the support 9 with a view to preventing casual movement of the clamp member 20 relative to the support 9 and in the direction of the length of

the rail 2. The inner portion of the clamp

20 rests over the adjacent edge of the rail base to hold the latter down on the block 15, and the aperture 21 in the clamp member 20 serves to receive a bolt 24 provided at 25 5 with a key adapted to be turned into the before mentioned chamber 16 in the support 9. The upper portion of the bolt 24 is threaded to receive a nut 26 which is adapted to bear on the clamp member 20 and 10 thereby enable the latter to hold the rail against upward movement.

Manifestly by virtue of my novel tie being formed in a plurality of sections connected together by links 3, the sections may 15 be conveniently handled in storage and shipment and when it is desired to assemble two of the bodies or sections for use they may be expeditiously and easily connected through the medium of the before mentioned 20 links 3, and this without the employment of skilled labor. It will also be appreciated that the bodies 1 of a single tie are capable of vertical movement each independently of the other, though endwise movement of 25 one body or section 1 with respect to the other is prevented.

It will also be manifest that rails may be expeditiously and easily connected to the bodies or sections 1 and as readily disconnected therefrom, though there is no liability of the rails becoming casually disconnected and no interference with the rails moving on the blocks 15 in the direction of 30 the length of the rails as is desirable.

35 An important feature of my invention resides in the fact that the metallic portion of each concrete body or section 1 is comparatively small in weight.

Another important feature of the invention 40 resides in the fact that all worn parts can be replaced without disturbing the tie or the rail.

In have entered into a detailed description 45 of the construction and relative arrangement of the parts embraced in the present and preferred embodiment of my invention in order to impart a full, clear and exact understanding of the said embodiment. I do not desire, however, to be understood

as confining myself to the specific construction and relative arrangement of parts inasmuch as in the future practice of the invention various changes and modifications may be made such as fall within the scope of my invention as defined in my appended 55 claims.

Having described my invention, what I claim and desire to secure by Letters-Patent, is:—

1. The combination with a concrete tie 60 body, of a longitudinal dished metallic reinforcement therein, and a metallic rail support anchored in the body and disposed above said longitudinal dish reinforcement, the said support having an upstanding web 65 longitudinal of the body and also having lateral portions and being recessed and engaged with a block disposed in said recess and being chambered and engaged with a rail clamp, a bolt extending through said 70 clamp and equipped with a nut and having a key adapted to rest in said chamber and being also engaged with a key seated in coincident recesses in the support and block and adapted to rest at the opposite side of 75 a rail base, with reference to said clamp.

2. The combination of a concrete body or section, and a metallic rail support embodied and anchored in said body and recessed and engaged with a resilient block disposed in 80 said recess and also chambered and engaged with a rail clamp and a bolt complementary to said clamp and having a key disposed in said chamber.

3. The combination of a concrete body or 85 section, and a metallic rail support embodied and anchored in said body and recessed and engaged with a resilient block disposed in said recess and also chambered and engaged with a rail clamp and a bolt complementary 90 to said clamp and having a key disposed in said chamber; the said support and block being provided with coincident recesses and being engaged with a reversible loose key.

95 In testimony whereof I affix my signature.

JAMES W. FALK.
